UNITED STATES PATENT OFFICE.

GEORGE P. YOUMANS, OF GALESBURG, MICHIGAN, ASSIGNOR TO KALAMAZOO TANK AND SILO CO., OF KALAMAZOO, MICHIGAN.

SILO.

1,151,644.

Specification of Letters Patent. Patented Aug. 31, 1915.

Application filed October 16, 1913. Serial No. 795,455.

To all whom it may concern:

Be it known that I, GEORGE P. YOUMANS, a citizen of the United States, residing at Galesburg, Michigan, have invented certain 5 new and useful Improvements in Silos, of which the following is a specification.

This invention relates to improvements in silos. The main objects of this invention are: First, to provide an improved block 10 wall silo. Second, to provide in a silo, an improved structure having a continuous door opening. Third, to provide in a silo, an improved wall reinforcing means. Fourth, to provide an improved silo which 15 is attractive in appearance and at the same time comparatively economical to produce.

Further objects, and objects relating to structural details, will definitely appear from the detailed description to follow.

20 I accomplish the objects of my invention by the devices and means described in the following specification.

The invention is clearly defined and pointed out in the claims.

25 A structure which is a preferred embodiment of my invention is clearly illustrated in the accompanying drawing forming a part of this specification, in which:

Figure I is a detail front elevation of a 30 structure embodying the features of my invention. Fig. II is a detail horizontal section on a line corresponding to line 2—2 of Fig. I. Fig. III is a detail horizontal section on a line corresponding to line 3—3 of Fig. 35 I. Fig. IV is a detail vertical section on a line corresponding to line 4—4 of Fig. II. Fig. V is a detail vertical section through the doors, on a line corresponding to line 5—5 of Fig. I. Fig. VI is a plan 40 view showing the joints of the sections of the reinforcing hooks 10.

In the drawing similar reference characters refer to similar parts throughout the several views, and the sectional views are 45 taken looking in the direction of the little arrows at the ends of the section lines.

Referring to the drawing, the structure 50 illustrated is a circular silo having a continuous door opening. The wall of the silo is formed of blocks 1 laid in cement or mortar 2. These blocks are preferably cement blocks or vitrified blocks or bricks.

At each side of the door opening are special blocks 3 which I designate as door casing blocks. These blocks 3 are hollow and

open at top and bottom so that when laid they form a continuous channel adapted to receive a filler 4 of concrete, the filler constituting continuous columns at each side of the door opening. This filler reinforces the 60 casing blocks and assists the mortar or cement in which they are laid, in keeping them in place in the wall. These blocks are shouldered at their inner ends, as at 5, their inner corners being preferably rounded to the 65 shoulders, as at 6.

The angle iron casing uprights 7 are arranged with their angles over the front angles of the shoulders. See Fig. II. These uprights 7 are held in position by the angle 70 iron cross bars 8. The cross bars are preferably provided with struck-in lugs 9 which engage the uprights, as shown in Fig. II, and may be riveted or otherwise secured to the front arms of the uprights, the securing 75 means not being shown.

The wall is provided with reinforcing or tie members or hoops 10 which are laid with their ends projecting into the hollow blocks and secured to the vertical tie rods 11 ar- 80 ranged therein. The filling 4 for the casing blocks embeds these tie rods and the projecting ends of the hoops or reinforcing members 10 so that they are supported in position. The tie rods constitute reinforcing members for the columns of filling material. These hoops 10 are formed of band 85 iron and laid flat between the tiers of bricks or blocks. This permits a thin cement joint. The hoops are given a quarter twist at 21 so 90 that they may be conveniently lapped around the tie rods 11. For convenience in handling the hoops are preferably formed in sections having corrugated joint portions 12, the joint portions being lapped so that 95 their corrugations engage when laid in the wall. These corrugations are clamped together, being, in fact, embedded with the weight of the wall thereon so that an effective joint is provided. At intervals I provide 100 continuous hoops 13 which extend across the door opening, the hoops 13 being preferably arranged over the cross bars 8.

The doors 15 are arranged to be superimposed one upon another and to close against 105 the inner sides of the casing blocks 3 which are provided with flattened portions adjacent to their inner ends which constitute door seats 16. See Fig. 11. The door hinges are preferably those described in my appli- 110

cation for Letters Patent filed October 28, 1912, Ser. No. 728,186.

The hinge members 17 are provided with pintles 18 on one of the casing uprights 5. The hinge members 17 are curved rearwardly at 19 to clear the casing when the doors are swung in. The clamping members 20 engage the opposite upright when the doors are closed and coact with the hinge members 17 in clamping the doors in place.

As the details of the hinges are fully described in my application for Letters Patent referred to and as they constitute no part of my present invention, I do not describe the same with further detail herein.

With the parts thus arranged, I secure a block wall silo having a continuous door opening, which is not likely to crack or bulge or otherwise get out of shape. The structure is very attractive in appearance and is at the same time quite economical to produce and is very durable.

I have illustrated and described my improvements in a desirable embodiment. I have not attempted to illustrate or describe certain modifications or changes in structural details which I contemplate, as I believe the disclosure made will enable those skilled in the art to which my invention relates to embody or adapt the same as conditions or taste may dictate. I desire, however, to be understood as claiming my improvements specifically in the form illustrated as well as broadly within the scope of the appended claims.

Having thus described my invention, what I claim as new and desire to secure by Letters Patent is:

1. In a silo, the combination with the wall having a continuous door opening and comprising a tier of hollow blocks at each edge of the door opening, said blocks being open at the top and bottom to provide a continuous vertical channel, the inner ends of the blocks being shouldered, their front inner corners being rounded to the shoulders, the inner sides of the blocks being flat adjacent their inner ends to provide door seats; angle iron casing uprights arranged with their angles over the front angles of the shoulders; cross bars extending between said uprights; hoops embedded in the wall with their ends projecting into said blocks; vertical tie rods to which said hoops are connected, disposed in said channels, said channels being filled with concrete constituting continuous columns and embedding said tie rods, the tie rods constituting reinforcing members for the columns; and hoops disposed at intervals to extend across the door opening, said hoops being arranged over said cross bars.

2. In a silo, the combination with the wall having a continuous door opening and comprising a tier of hollow blocks at each edge of the door opening, said blocks being open

at the top and bottom to provide a continuous vertical channel, the inner ends of the blocks being shouldered; angle iron casing uprights arranged with their angles over the front angles of the shoulders; cross bars extending between said uprights; hoops embedded in the wall with their ends projecting into said blocks; vertical tie rods to which said hoops are connected, disposed in said channels, said channels being filled with concrete constituting continuous columns and embedding said tie rods, the tie rods constituting reinforcing members for the columns; and hoops disposed at intervals to extend across the door opening, said hoops being embedded in said wall to project from the ends of said shouldered blocks in front of their shoulders and over said uprights and cross bars.

3. In a silo, the combination with the wall having a continuous door opening and comprising a tier of hollow blocks at each edge of the door opening, said blocks being open at the top and bottom to provide a continuous vertical channel, the inner ends of the blocks being shouldered, the front inner corners being rounded to the shoulders, the inner sides of the blocks being flat adjacent their ends to provide door seats; angle iron casing uprights arranged with their angles over the front angles of the shoulders; cross bars extending between said uprights; reinforcing members disposed with their ends projecting into said blocks; and vertical tie rods to which said reinforcing members are connected, disposed in said channels, said channels being filled with concrete constituting continuous columns and imbedding said tie rods, the tie rods constituting reinforcing members for the columns.

4. In a silo, the combination with the wall having a continuous door opening and comprising a tier of hollow blocks at each edge of the door opening, said blocks being open at the top and bottom to provide a continuous vertical channel, the inner ends of the blocks being shouldered; angle iron casing uprights arranged with their angles over the front angles of the shoulders; cross bars extending between said uprights; reinforcing members disposed with their ends projecting into said blocks; vertical tie rods to which said reinforcing members are connected, disposed in said channels, said channels being filled with concrete constituting continuous columns and embedding said tie rods, the tie rods constituting reinforcing members for the columns and hoops disposed at intervals to extend across said door openings, said hoops being embedded in said wall to project from the ends of said shouldered blocks in front of their shoulders and over said uprights and to engage the outer side of said tie rods.

5. In a silo, the combination with the wall

- having a continuous door opening and comprising a tier of blocks at each edge of the door opening, the inner ends of the blocks being shouldered, the front inner corners being rounded to the shoulders, the inner sides of the blocks being flat adjacent their ends to provide door seats; angle iron casing uprights arranged with their angles over the front angles of the shoulders; cross bars extending between said uprights; and hoops disposed at intervals to extend across the door opening, said hoops being arranged over said uprights whereby they are supported.

6. In a silo, the combination with the wall having a continuous door opening and comprising a tier of blocks at each edge of the door opening, the inner ends of the blocks being shouldered; angle iron casing uprights arranged with their angles over the front angles of the shoulders; cross bars extending between said uprights; and hoops disposed at intervals to extend across the door opening, said hoops being embedded in said wall to project from the ends of said shouldered blocks in front of their shoulders and over said uprights whereby the uprights are supported on said shoulders.

7. In a silo, the combination with the wall having a continuous door opening and comprising a tier of blocks at each edge of the door opening, the inner ends of the blocks being shouldered, the front inner corners being rounded to the shoulders, the inner sides of the blocks being flat adjacent their ends to provide door seats; angle iron

casing uprights arranged with their angles over the front angles of the shoulders; doors adapted to be superimposed and to close from the inside against said seats on said blocks; hinge members pivoted on said uprights, said hinge members being curved rearwardly at their pintle ends to clear the casing when swung through the opening; and securing members associated with said hinge members to engage the other casing upright when the doors are closed, all coacting for the purpose specified.

8. In a silo, the combination with the wall having a continuous door opening and comprising a tier of blocks at each edge of the door opening, the inner ends of the blocks being shouldered; angle iron casing uprights arranged with their angles over the front angles of the shoulders; doors adapted to be superimposed and to close from the inside against said blocks; hinge members pivoted on said uprights, said hinge members being curved rearwardly at their pintle ends to clear the casing when swung through the opening; and securing members associated with said hinge members to engage the other casing upright when the doors are closed, all coacting for the purpose specified.

In witness whereof, I have hereunto set my hand and seal in the presence of two witnesses.

GEORGE P. YOUMANS. [L.S.]
